2 SHEETS—SHEET 2.

UNITED STATES PATENT OFFICE.

WALTER L. ASHMORE AND HOMER R. POWELL, OF MACON, GEORGIA.

DEVICE FOR FINISHING CONCRETE PAVEMENTS.

1,364,605.

Specification of Letters Patent.

Patented Jan. 4, 1921.

Application filed July 25, 1919. Serial No. 313,171.

To all whom it may concern:

Be it known that we, WALTER L. ASHMORE and HOMER R. POWELL, citizens of the United States, residing at Macon, in the county of Bibb and State of Georgia, have invented certain new and useful Improvements in Devices for Finishing Concrete Pavements; and we do hereby declare the following to be a full, clear, and exact description of the invention, such as will enable others skilled in the art to which it appertains to make and use the same.

This invention relates to means for rolling, smoothing and finishing concrete pavements and the like and more particularly to rolling devices adapted to produce a tamping effect when moved over the surface of concrete which is spread over the road bed as it comes from the mixing machine.

20 The primary object of our invention is to provide a simple and efficient rolling device of the character referred to having means to effect a tamping action as it is drawn or moved to and fro over the surface of the 25 concrete mass.

The invention will first be hereinafter more particularly described, with reference to the accompanying drawings, which are to be taken as a part of this specification, 30 and then pointed out in the claims at the end of the description.

In said drawings, Figure 1 is a plan view of a rolling and tamping device embodying our invention;

35 Fig. 2 is a front view of the same;

Fig. 3 is a side view thereof, not showing the engine;

Fig. 4 is a vertical longitudinal sectional view illustrating a modification of the invention.

Fig. 5 is a side view of another modification, and Fig. 6 is a front view, partly in section, of the device shown in Fig. 5.

40 Referring to said drawings, in which the same reference letters are used to denote corresponding parts in different views, the letters A, A¹ and A² denote the front, rear and side plates, respectively, of a supporting frame, having journaled therein a group of 45 rollers B, B¹ and B², which are preferably of the type shown in Letters Patent No. 1,273,022, issued July 16, 1918, to W. L. Ashmore and W. T. Morgan, Jr., for a process and device for finishing concrete pavements.

50 55 The rollers are preferably hollow and are

of small diameter and relatively great length and light weight, to adapt the device to float on oversaturated concrete and to act on the surface thereof as a straight edge, for straightening and smoothing such surface. 60 These rollers may have axles which extend therethrough or stub shafts journaled in suitable bearings in the side plates A² of the supporting frame, said side plates being preferably constructed of thin sheet metal or steel, 65 bolted or otherwise secured to similar front and rear plates so as to form a square or rectangular frame. Said frame, in the form shown in Figs. 1 to 3, is constructed in two sections which are hinged together at an intermediate point, coincident with the axis of the intermediate roller B², so as to adapt the latter roller to move upwardly and downwardly as the device is moved over the surface of the paving material. The letter C 70 denotes a gas engine mounted on the supporting frame, preferably a two-cycle engine having a reciprocating piston with a piston rod having its free end pivotally attached to a crank or crank arms on a crank-shaft D, having pinions d thereon in mesh with pinions or gear wheels e on the inner ends of shafts E, E, which have cranks e¹ on their outer ends carrying studs or pins e² from which are suspended connecting rods 80 or bars F, the lower ends of which have eyes to receive the projecting ends of the roller shaft, or stub shafts projecting from the heads of the intermediate roller B², and on which the two sections of the supporting 85 frame are hinged, so that by the rotation of the crank shaft D and with it the crank shafts E, E a reciprocatory movement will be imparted to the connecting rods F, thereby raising and lowering the center of 90 the hinged frame and with it the intermediate roller, once during each revolution of the crank shaft or each reciprocating movement of the piston of the gas engine. This movement tends to draw the two outside or 95 front and rear rollers together or toward each other, and at the same time, as the intermediate roller is lifted, throws the entire thrust of the weight on said outside rollers, thus producing a pinching or kneading effect 100 on the paving material, while the downward thrust or movement of the intermediate roller has a tamping effect, thus causing the coarse aggregate or heavier particles to sink downwardly, while the finer and lighter 105 110

particles are caused to rise to the surface sufficiently to form a smooth finished pavement.

For tamping very stiff concrete or brick pavements and other tamping work, we detach the middle roller B^2 and substitute therefor a tamping bar B^3 (Fig. 4), which is supported and actuated or lifted and depressed successively in the same manner and 5 by the means hereinbefore described for operating the intermediate tamping roller. Otherwise the construction of the rolling and tamping device shown in Fig. 4 is essentially the same as described with reference 10 to the construction and arrangement of parts shown in Figs. 1 to 3.

In the modifications shown in Figs. 5 and 6, a rigid or inflexible frame is employed and the intermediate roller has its axle ends 20 or stub shafts on the roller heads projecting through vertically disposed elongated slots g in the side bars A^2 of the supporting frame, to allow vertical movement of the intermediate roller, which may be raised and 25 lowered or lifted and depressed by connecting the rods F with the axle ends or stub shafts of said roller in the manner shown and described with reference to Figs. 1 to 3 of the drawings, but in this instance we have 30 shown an engine provided with a fly wheel or crank-shaft, which is connected by a rod h with the inner ends of a pair of levers H, H , which are fulcrumed on standards I on the supporting frame and have connecting rods 35 F^2 suspended from their free ends, said rods F^2 being provided at their lower ends with apertures to receive the ends of the roller-shaft or axle or stub shafts projecting from the roller heads of the intermediate 40 roller, whereby the latter roller may be lifted and depressed once during each revolution of the crank shaft of the engine, thus forming a tamp of the middle roller.

For the purpose of propelling or drawing 45 the rolling device over the surface of the paving material, it may be provided with a long handle, or two handles, one projecting from the front and another from the rear thereof, but preferably a rope is attached to 50 each end of the front and rear of the carriage or supporting frame whereby it may be pulled across the street or back and forth over the surface of the paving material by an operator at each edge of the pavement, 55 so as to avoid the necessity for and prevent the operator from standing on the freshly laid concrete, which tends to form mortar pockets by the feet pressing the coarse aggregate down lower than the surrounding 60 surface.

The operation and advantages of our invention will be readily understood from the foregoing description. Freshly laid over-saturated concrete being spread over the 65 road bed as it comes from the mixing ma-

chine, our rolling device is placed thereon and moved back and forth, and by the tamping effect of the intermediate roller the coarse aggregate and heavier particles are caused to settle down, while the lighter and finer particles are caused to rise to the surface sufficiently to form a smooth finished pavement, which when finished is not liable to develop check cracks and is more compact and durable than concrete pavements as 70 heretofore ordinarily constructed.

The described movement of the rollers, in addition to the direct blow or tamping effect of the middle roller, greatly expedites the 75 progress of the work of tamping and finishing the pavement. While specially designed for use in smoothing and finishing concrete pavements, in which oversaturated concrete is used, the device is capable 80 of use on other types of pavements, and particularly on what is known as monolithic brick pavements.

Having thus described our invention, what we claim is:

1. A device for rolling and tamping concrete pavements, comprising a group of rollers journaled in a supporting frame having front and rear sections hinged together, an intermediate vertically movable roller, and a motor on said frame connected to and 90 adapted to impart a rapid upward and downward movement to the intermediate roller.

2. A device for rolling and tamping concrete pavements, comprising a group of rollers journaled in a supporting frame, said frame having flexibly connected front and rear sections, one of the intermediate rollers being movable vertically while moving horizontally over the surface of the concrete, 100 and a motor and means on said frame adapted to cause said movable roller to move quickly up and down so as to effect a tamping action thereof.

3. The combination in a device for rolling 110 and tamping paving material, of a frame having front and rear flexibly connected sections and having three rollers journaled therein, the intermediate roller being movable upwardly and downwardly at the point 115 of flexure of the frame as the device is moved over the surface of the paving material, and a motor mounted on said frame having a piston and connections between said piston and said intermediate roller 120 whereby the roller is rapidly lifted and depressed so as to effect a tamping action as it is moved over said surface.

4. A device for finishing and smoothing concrete pavements, comprising a group of 125 rollers journaled in a supporting frame, said frame being hinged at an intermediate point with provision for vertical reciprocatory movement thereof, one roller being arranged at said point, a motor mounted on said 130

frame, and connections between said motor and said intermediate roller adapted to effect an upward and downward movement or tamping action thereof as the machine is 5 moved to and fro over the surface of the concrete.

5. A device for smoothing and finishing concrete pavements and the like, comprising a supporting frame having a plurality of 10 rollers journaled therein, one of said rollers being located about midway of the length of the frame between other rollers, said frame having front and rear sections hinged together on a line passing through said midway roller, a motor on said frame, and connections between said motor and supporting frame whereby said midway roller is lifted and depressed in rapid succession so as to effect a tamping action thereof as the device 15 is moved over the surface of the concrete.
6. A device for finishing pavements comprising several rollers of small diameter and relatively great length and light weight journaled in a supporting frame in the same 20 horizontal plane, one roller being arranged 25 at an intermediate point between other roll-

ers, and said frame having front and rear sections hinged together at said intermediate point, a motor on said frame, and means connecting said motor and frame whereby 30 the intermediate portion of the frame and with it the intermediate roller may be raised and lowered in such manner as to effect a kneading action on the paving material and a tamping action of the intermediate roller. 35

7. A device for rolling, tamping and finishing concrete and other pavements, comprising a frame having front and rear flexibly connected sections and carrying a plurality of rollers and a vertically movable 40 roller or tamping device arranged between front and rear rollers, a motor carried by said frame, and means actuated by said motor for imparting an upward and downward movement to said tamping device. 45

In testimony whereof we affix our signatures in the presence of two witnesses.
